(21) Appl. No.: 29/134,247

(57) CLAIM

(22) Filed: Dec. 15, 2000

I claim the ornamental design for a front of a bodysuit, as shown and described.

(51) LOC (7) Cl. 02-02

DESCRIPTION

(52) U.S. Cl. D2/733

The FIGURE is a front elevational view of a front of a bodysuit, showing my new design with the side and rear portions thereof not shown, being disclaimed.

(58) Field of Search D2/714, 719, 733;
2/80, 83, 109, 111

The design is characterized by leg and torso portion of a garment having an opening in the torso portion.

(56) References Cited

The broken line showing of the bodysuit is for illustrative purposes only and forms no part of the claimed design.
